F. L. WITHAM

VALVE SPRING COMPRESSING DEVICE

Filed Jan. 9, 1924

UNITED STATES PATENT OFFICE.

FRANK L. WITHAM, OF PETALUMA, CALIFORNIA.

VALVE-SPRING-COMPRESSING DEVICE.

Application filed January 9, 1924. Serial No. 685,196.

To all whom it may concern:

Be it known that I, FRANK L. WITHAM, a citizen of the United States, residing at Petaluma, county of Sonoma, and State of California, have invented new and useful Improvements in Valve-Spring-Compressing Devices, of which the following is a specification.

This invention relates to a tool for use 10 in handling the helical valve springs of engine poppet valves.

At the present time it is difficult to conveniently and quickly remove and replace the coil springs used in connection with the 15 poppet valves of automobile engines. This is due partly to the fact that the springs must be compressed in order to replace them and that there is difficulty in placing them in position due to the limited space allowed 20 for the valve springs in the engine design. With this idea in view it is the principal object of the present invention to provide simple means for handling these springs, compressing them and holding them under 25 a condition of compression until they have been placed in their operative position relative to the stem of the poppet valve.

The present invention contemplates the use of a base member and a plurality of 30 dogs which may be caused to automatically embrace the sides of the valve spring and to hold the valve spring in a compressed condition until such time as it is desired to release the spring.

35 The invention is illustrated by way of example in the accompanying drawings, in which:

Fig. 1 is a view in side elevation showing the present invention and its mode of operation.

40 Fig. 2 is an enlarged fragmentary view in end elevation showing the receiving groove for the spring dogs.

Fig. 3 is a view in side elevation showing 45 a valve spring compressed and held in its compressed position by the dogs.

Fig. 4 is a modified form of the present invention showing adjustable jaws for supporting the dogs prior to the time they embrace the springs.

50 Figure 5 is a fragmentary view in end elevation of the modified form of the invention disclosed in the preceding figure and illustrating the mounting of the adjustable jaws on the base member.

Referring more particularly to the draw-

ing 10 indicates a base member which is here shown as formed with a horizontal table portion 11 and a plurality of supporting legs 12. Formed longitudinally of the table and across the horizontal plane face thereof is a groove 13 for receiving the lower ends of dogs 14. The floor of the groove is flat and the side walls extend at right angles thereto, thus insuring that the dogs will be held in aligned positions relative to each other for a purpose which will be herein-after described.

The dogs, as shown in Fig. 3, are formed with straight body members which may be made of rectangular sectioned stock and which body portions terminate in a head and a foot 15 and 16, respectively, at the opposite ends of the dogs. The head 15 forms a hook which will assume an overhanging position at the top of the spring and will engage the washer 16 usually associated with the spring when assembled. The end of the head is inclined as indicated at 17 to insure that the spring will ride down over the head as it is compressed. The foot 16 projects outwardly from the same side of the dog as the head and forms a hook which engages the lower end of a spring 18. The end face of the foot tapers inwardly to form a heel at the outer end of the foot so that when this heel rests against the flat floor of the groove 13 and pressure is exerted on the foot the dog will tend to swing inwardly from the dotted line position shown in Fig. 1 to the full line position shown in the same figure.

As here shown two dogs are provided. It will be understood that any number might be used if a preliminary support for them is furnished. The dogs are preferably secured together by a chain 19 which makes it possible for them to be conveniently jerked away from the spring when the spring is to be released. Compression of the spring is brought about by a member 20 which comprises a handle 21 and a shaft 22. This shaft extends downwardly through a central opening 23 in the table and through a boss 24 formed beneath the table to serve in lengthening the bearing for the shaft. The opening 23 extends directly through the center of the groove 13 in the face of the table and is disposed substantially midway the length of this groove.

In the form of the invention shown in Fig. 4 dogs 14 are utilized as has been pre-

viously described, but these dogs are temporarily set on movable jaws 25 which may slide along ways toward and from each other as guided by a base plate 26 on which they are mounted. The movable jaws 25 are mounted between two plates 25^a which are arranged on the base plate 26. Extending through these plates 25^a are transverse pins 25^b. The ends of these pins 25^b are engaged 5 by eyelets 25^c which are threaded into the upper surface of the base plate 26. The movable jaws 25 are provided with slots 25^d which engage the pins 25^b so that the jaws may be moved toward and away from each other between the plates 25^a. These jaws are made movable so that springs of different diameter may be accommodated. The faces of the jaws which support the dogs diverge from the base plate to dispose the 10 dogs at an angle to each other so that the upper ends of the dogs will swing inwardly under pressure on the spring and automatically hook over the washer 16 when the spring has been properly compressed.

25 In operation of the present invention as shown in Figs. 1 and 2 the expanded spring is placed on the table 11. The washer 16 is then positioned over the upper end of the spring and the shaft 22 is then passed downwardly through the opening in the washer and the center of the spring. The shaft then passes through the guide opening 23 in the table and the boss 24. The dogs 14 may then be positioned with their feet in the grooves 30 and with the projecting portions of the feet disposed beneath the lower end of the spring. These dogs may be held in such position, as indicated in dotted lines in Fig. 1, by one hand of the operator, while the other hand is being used in exerting pressure on the handle 21. As pressure is thus exerted the flange 21^a of the handle will rest upon the washer 16 and continued pressure will tend to compress the spring. This action 35 will be accompanied by a tendency of the dogs to swing inwardly due to the tapered faces of the feet so that when the spring is compressed to a point where the head is free to pass over the top of the spring the force exerted on the handle will tend to swing the head of the dog over the washer and to an aligned position along the side of the spring. Pressure may then be released from the handle 40 so that expansion of the spring may then take place between the hook faces of the dogs to thus hold the dogs in position. The handle 21 and the associated shaft, therefore, may then be removed and the spring may be carried from place to place as desired. The 45 condition of the spring and dogs after being disassociated from the compression device is shown in Fig. 3. It will be evident that the spring may then be placed in a substantially inaccessible mounting if necessary and that 50 after the valve stem has been properly fixed 55

a jerk on the chain 19 will remove the spring so that it will be expanded in its proper working position.

In the form of the invention shown in Fig. 4 the procedure is substantially the same, 70 other than that the dogs are temporarily supported on the diverging faces of the movable jaws.

While I have shown the preferred form of my invention as now known to me, it will 75 be understood that various changes might be made in the combination, construction and arrangement of parts by those skilled in the art, without departing from the spirit of the invention as claimed.

Having thus described my invention what I claim and desire to secure by Letters Patent is:

1. A device of the character described comprising a base member, a plurality of 85 dog members adapted to be positioned by the base member, and compression means whereby a helical spring may be forced down upon the base member to permit the dogs to embrace the spring longitudinally 90 and hold it in its compressed condition, said base and dogs cooperating to insure that the spring when compressed will be automatically engaged by the dogs.

2. A device of the character described 95 comprising a base upon which a helical spring may rest, a plurality of dogs adapted to assume positions longitudinally of the spring and embrace the same to prevent expansion thereof, means forming a part of 100 the base member for operatively positioning the dogs relative to a spring, and compression means for exerting force upon the spring to cause it to be compressed sufficiently to be embraced by the dogs.

3. A device of the character described comprising a base formed with a plane top face, a longitudinally extending groove formed in the top face and having a horizontal floor and perpendicular side walls, a 110 pair of dogs having widths substantially equal to the distance between said perpendicular side walls and being formed with hook flanges at their opposite ends, a centering hole passing perpendicularly through the base and through the slot in the face thereof, and a compressing tool formed with a spindle adapted to extend through the centering hole and acting to exert force upon a helical spring resting upon the plane face of the base whereby it will be compressed and will be longitudinally embraced by the dogs.

4. A device of the character described comprising a base formed with a plane top face, a longitudinally extending groove formed in the top face and having a horizontal floor and perpendicular side walls, a pair of dogs having widths substantially 125 equal to the distance between said perpen- 130

icular side walls and being formed with hook flanges at their opposite ends, a centering hole passing perpendicularly through the base and through the slot in the face thereof, a compressing tool formed with a spindle adapted to extend through the centering hole and acting to exert force upon a

helical spring resting upon the plane face of the base whereby it will be compressed and will be longitudinally embraced by the dogs, and means formed as a part of the dogs for causing them to swing inwardly at their upper ends to engage the compressed spring. **10**
